UNITED STATES PATENT OFFICE.

LUTHER B. BAILEY, OF LONDON, ONTARIO, CANADA.

LUBRICATOR.

SPECIFICATION forming part of Letters Patent No. 256,869, dated April 25, 1882.

Application filed August 10, 1881. (No model.)

To all whom it may concern:

Be it known that I, LUTHER BYRON BAILEY, a subject of the Queen of Great Britain, residing at the city of London, in the county of 5 Middlesex, in the Province of Ontario, Canada, have invented a new and useful Lubricator, of which the following is a specification.

My invention consists of a lubricator in which the steam-inlet and lubricant-outlet are through 10 one and the same passage, thereby requiring only one connection from lubricator to the steam-pipe or steam-chest. This is effected by a valve-chamber of peculiar construction, in combination with a lubricant-reservoir and 15 gage-glass.

The construction and operation will be more particularly explained with reference to the accompanying drawings, wherein—

Figure 1 is a side elevation of my invention. 20 Fig. 2 is an end view of same. Fig. 3 is a vertical section, and Fig. 4 is a horizontal section, of valve-chamber.

P is a steam-pipe or steam-chest, to which the lubricator L is screwed or otherwise connected. 25

R is a lubricant-reservoir, at bottom of which is valve-chamber V, containing valves O O'; and G is a gage-glass for the purpose of noting the supply of the lubricant to the steam-pipe 30 or steam-chest, and to tell when the lubricant has run out.

C is the cap of the lubricator, through which the lubricant is introduced into the reservoir R. The steam from the steam-pipe enters 35 valve-chamber V (the construction of which is shown more particularly in Figs. 3 and 4) through passage S, and the steam acts on the oil in reservoir R through either valve, ac-

cording as the valves are more or less open. The reservoir R has communication with the 40 passage S through two ducts: first, through the passages r and s, and, second, through the gage-glass G (entering the reservoir at g) and passages r' and s'. By closing valve O and opening valve O' the steam enters the oil-reservoir R directly from valve-chamber V and presses on the oil, and by slightly opening the valve O the steam forces the lubricant out of reservoir R at side, down through gage-glass G into the valve-chamber V, and delivers the 50 lubricant at the back of the valve O, which regulates the supply of oil passing into the steam-pipe through passage S. If by accident the passage S through the gage-glass G should become choked or stopped up from any 55 cause whatever, by closing valve O' and opening valve O the steam is forced directly from valve-chamber through the gage-glass and blows out the obstruction, which forces the oil out of the reservoir R at the bottom into valve-chamber, the supply of oil to the steam-pipe 60 or steam-chest in this case being regulated by the distance the valve O' is opened.

Having thus described my invention, I 65 claim—

The combination, with reservoir R, having steam-passage r at bottom and oil-outlet g at top, of valve-chamber V, having communication with said reservoir at bottom through the valve-passage r s, and at top through the outlet g, glass tube G, and valved passage r' s', as set forth.

LUTHER BYRON BAILEY.
